UNITED STATES PATENT OFFICE

168,367

BATTERY KIT CONTAINER

Van Nelson, Monterey Park, Calif., assignor to
Pacific Hard Rubber Company, a corporation
of California

Application August 9, 1952, Serial No. 20,963

Term of patent 14 years

(Cl. D26—6)

To all whom it may concern:

Be it known that I, Van Nelson, a citizen of the United States and a resident of the city of Monterey Park, county of Los Angeles, State of California, have invented a new, original, and ornamental Design for a Battery Kit Container, of which the following is a specification, reference being had to the accompanying drawing, forming a part thereof.

Figure 1 is a perspective view of a battery kit container showing my new design.

Figure 2 is a perspective view illustrating the side and bottom construction thereof.

Figure 3 is a top perspective view thereof.

I claim:

The ornamental design for a battery kit container, as shown.

VAN NELSON.
